US00D936650S

(12) **United States Design Patent** (10) **Patent No.:** **US D936,650 S**
(45) **Date of Patent:** **** Nov. 23, 2021**

(54) **SMARTWATCH**

(71) Applicant: **VitalTech Properties, LLC**, Plano, TX (US)

(72) Inventors: **Anjan Panneer Selvam**, Plano, TX (US); **James Hamilton**, Southlake, TX (US); **Qing Sun**, Plano, TX (US); **Peter Ianace**, Frisco, TX (US)

(73) Assignee: **VITALTECH PROPERTIES, LLC**, Plano, TX (US)

(**) Term: **15 Years**

(21) Appl. No.: **35/509,377**

(22) Filed: **Oct. 18, 2019**

(80) **Hague Agreement Data**

Int. Filing Date: **Oct. 18, 2019**

Int. Reg. No.: **DM/207978**

Int. Reg. Date: **Oct. 18, 2019**

Int. Reg. Pub. Date: **May 15, 2020**

(51) **LOC (13) Cl. 14-02**

(52) **U.S. Cl.**

USPC **D14/344**; D24/167

(58) **Field of Classification Search**

USPC D10/30, 32, 38; D11/3, 5; D14/341, D14/344; D24/167

CPC A44C 5/0053; A44C 5/145; G06F 1/163

See application file for complete search history.

(57) **CLAIM**

The ornamental design for a smartwatch, as shown and described.

DESCRIPTION

1. Smartwatch

1.1 : Top, rear perspective view

1.2 : Top, front perspective view

1.3 : Front view

1.4 : Rear view

1.5 : Left view

1.6 : Right view

1.7 : Left view

1.8 : Bottom view

1.9 : Bottom, front perspective view

1 Claim, 9 Drawing Sheets
